His Attorney.

UNITED STATES PATENT OFFICE

AUGUSTUS B. TRIPP, OF CLIFTONDALE, MASSACHUSETTS, ASSIGNOR TO GENERAL ELECTRIC COMPANY, A CORPORATION OF NEW YORK

OSCILLATION GENERATOR

Application filed June 4, 1928. Serial No. 282,575.

My invention relates to electric oscillation generators which are operated at a frequency determined by a piezo electric element, such as a quartz crystal or the like, and has for its principal object the provision of an improved arrangement and method of operation whereby the piezo electric element is protected from injury and the output of the generator is materially increased.

In the operation of oscillation generators provided with a frequency determining element such as a quartz crystal, difficulty has been heretofore encountered due to the tendency of the crystal to spark. Such sparking is likely to produce overheating or fracture of the crystal. I have discovered that this difficulty may be avoided and that the output of the crystal may be materially increased by connecting in parallel with the crystal a device which begins to transmit current when subjected to a predetermined voltage.

My invention will be better understood from the following description when considered in connection with the accompanying drawing and its scope will be pointed out in the appended claims.

The drawing is a wiring diagram of an oscillation generator wherein my invention has been embodied.

This generator includes input terminals 1 and 2 and output terminals 3 and 4 which are interconnected through a space discharge device 5 which is provided with a cathode 6, a grid 7 and an anode 8. Current is supplied from a suitable source to the output circuit of the apparatus through supply terminals 9.

Three parallel circuits are connected in the input circuit of the device 5. One of these circuits includes a reactor 10, a resistor 11 and a grid bias battery 12. Another of these circuits includes a piezo electric element 13 and the remaining circuit includes a glow tube 14 or the like which begins to transmit current only when the potential of the crystal 13 exceeds a predetermined value.

In the operation of the invention, it has been found that the glow tube 14 acts as a

small capacitance in parallel with the crystal 13 and does not interfere with the starting and operating characteristics of the apparatus. If the amplitude of the crystal voltage reaches the break-down voltage of 55 the glow tube, however, the tube begins to carry current and the rapid increase in the oscillation amplitude of the crystal which would otherwise occur is prevented.

As will be readily appreciated by those experienced in the operation of piezo electric crystals, this is of great advantage in that fracture of the crystal due to violent oscillations is prevented. While the action of the glow tube in increasing the generator 60 output is not altogether understood, it has been found as the result of repeated observations that this result is consistently produced. It will of course be understood that any device having the same characteristics 65 as the glow tube may be utilized to protect the piezo electric crystal and increase the output of the generator.

The embodiment of the invention illustrated and described herein has been selected 70 for the purpose of clearly setting forth the principles involved. It will be apparent, however, that the invention is susceptible of being modified to meet the different conditions encountered in its use and I therefore aim to cover by the appended claims all 75 modifications within the true spirit and scope of my invention.

What I claim as new and desire to secure by Letters Patent of the United States, is:

1. An electric apparatus including an electron discharge device having an output circuit, and an input circuit including a piezo electric element, said output circuit and input circuit being so arranged that oscillations having the natural frequency of said piezo electric element are produced in said output circuit, and means for increasing the intensity of said oscillations in the output circuit, said means comprising a discharge path connected in shunt with said piezo electric element.

2. The combination, in an oscillation generator, of an electron discharge device having an input circuit including a piezo elec-

tric element, and an output circuit in which oscillations are produced having the natural frequency of the piezo electric element, and means for increasing the intensity of said oscillations in the output circuit, said means comprising a discharge device adapted to transmit current between its electrodes only when the potential therebetween exceeds a predetermined value, the electrodes of said discharge device being connected to opposite sides of said piezo electric element.

3. The combination in an oscillation generator, of an electron discharge device having an anode, a cathode, and a grid, a piezo

15

electric element connected between the cathode and grid, an oscillatory circuit connected between the anode and cathode in which oscillations having the natural frequency of said piezo electric element are produced, and a second electron discharge device connected in shunt with said piezo electric element, said second electron discharge device being adapted to transmit current between its electrodes only when the potential across said electrodes exceeds a predetermined value.

AUGUSTUS B. TRIPP.
